CLAIM

The ornamental design for an ellipse lamp, as shown and described.

DESCRIPTION

FIG. 1 is a perspective view of the ellipse lamp according to a first embodiment of the present invention;

FIG. 2 is a front view thereof, the rear view being a mirror image;

FIG. 3 is a right side view thereof, the left side view being a mirror image;

FIG. 4 is a top view thereof;

FIG. 5 is a bottom view thereof;

FIG. 6 is a perspective view of the ellipse lamp according to a second embodiment of the present invention;

FIG. 7 is a front view thereof, the rear view being a mirror image;

FIG. 8 is a right side view thereof, the left side view being a mirror image;

FIG. 9 is a top view thereof;

FIG. 10 is a bottom view thereof;

FIG. 11 is a perspective view of the ellipse lamp according to a third embodiment of the present invention;

FIG. 12 is a front view thereof, the rear view being a mirror image;

FIG. 13 is a right side view thereof, the left side view being a mirror image;

FIG. 14 is a top view thereof;

FIG. 15 is a bottom view thereof;

FIG. 16 is a perspective view of the ellipse lamp according to a fourth embodiment of the present invention;

FIG. 17 is a front view thereof, the rear view being a mirror image;

FIG. 18 is a right side view thereof, the left side view being a mirror image;

FIG. 19 is a top view thereof; and,

FIG. 20 is a bottom view thereof.

The broken lines shown are for illustrative purposes only and form no part of the claimed design.
